UNITED STATES PATENT OFFICE.

FRANK MAROVITCH, OF NELSON, BRITISH COLUMBIA, CANADA.

DRILLING-MACHINE.

1,217,617.

Specification of Letters Patent. Patented Feb. 27, 1917.

Application filed December 13, 1915. Serial No. 66,663.

To all whom it may concern:

Be it known that I, FRANK MAROVITCH, a subject of the Emperor of Austria-Hungary, residing at Nelson, in the Province of 5 British Columbia and Dominion of Canada, have invented certain new and useful Improvements in Drilling-Machines, of which the following is a specification.

An object of my invention is to provide 10 a mechanical hand operated tool which can be used in the place of the usual pneumatic tool for boring or drilling in rocks, for heading over rivets, and in other connections of a like nature.

15 A further object is to so construct the parts that the machine may be made of a size to be readily handled and will at the same time give a sharp and severe blow as well as a maximum number of such blows for the 20 manual efforts required.

A still further object is to construct the parts in a manner that when the machine is being used for rock drilling, a blast is being directed down through the drill by 25 the normal working of the machine to blow the dust and cuttings from beneath the drill, and that when the machine is used to head over rivets the air compressing means may be released.

30 With these and other objects in view, which will be later set forth, my invention consists in certain novel features of construction and combinations of parts which will be described in connection with the accompanying drawings and pointed out in the claims.

In the drawings:

Figure 1 is a view in side elevation of the machine.

40 Fig. 2 is a transverse vertical sectional view through the structure disclosed in Fig. 1, to show the operating parts.

Fig. 3 is a cross sectional view on the line 3—3 of Fig. 2.

45 Fig. 4 is a view in perspective showing the piston and hammer in a disassembled relation.

The machine comprises a casing 1 which has a cylinder 2 secured in an opening 3 50 formed in the lower part thereof and this casing 1 has the bearings 4 and 5 provided at spaced apart points at one side thereof.

A driving gear 6 has a stub shaft 7 formed 55 as a part thereof and this stub shaft 7 is mounted in the bearing 4, a pinion 8 being mounted by a stub shaft 9 in the bearing

5 in a relation to mesh with the gear wheel 6. An operating handle 10 is secured on the outer end of the stub shaft 7 by a set screw 11 and as this handle 10 is manually moved, the driving gear 6 will be caused to turn and through meshing with the pinion 8 will cause the stub shaft 9 to be revolved.

The stub shaft is held in the bearing 5 by a head 12 and on its inner end has an eccentric disk 13 secured, this eccentric disk being provided with the crank pin 14. An oil hole at 15 is provided through the upper part of the casing 1 to permit proper lubrication of the working parts and if desired 60 the parts might be provided with ball bearings and other mechanical expedients resorted to to reduce the friction and make the parts easier to operate.

The cylinder 2 has a shoulder 16 formed 75 on the interior wall thereof at a point above the lower end, and this shoulder has the bore thereof formed as a bearing to receive the hammer block 17 which is mounted to have endwise sliding movement. The lower end 80 of the cylinder 2 is provided with internal screw threads and a bushing 18 is mounted in the screw threaded end and is formed in its bearing portion to receive the shank end of a rock drill 19, or other tool to be 85 operated by the machine. In the present instance, the drill 19 is shown as having an octagonal-shaped shank 20 and it will, of course, be understood that the bearing socket 21 of the bushing 18 will be made octagonal 90 and of a slightly greater diameter than the cross dimension of the shank 20 so that this shank may have relatively free sliding movement within the bushing. The hammer block 17 is provided with a shoulder 22 95 around the lower end thereof which prevents too great movement of the same in an upward direction through the bearing of the shoulder 16 and as the shank 20 of the tool is fitted through the bushing, this shank 100 bears at its upper end against the lower end of the hammer block and when the cutting end 23 of the drill is in bearing engagement against the rock, the hammer block 17 is held with its upper end projecting into 105 the cylinder above the shoulder 16 and with the portion 22 thereof in bearing engagement with the lower side of the shoulder.

A piston 24 is mounted in the upper end 110 of the cylinder 2 at a point adjacent the connection of the same with the casing 1 and a connecting rod 25 is connected with

the piston 24 by the wrist pin 26 and has its free end mounted on the crank pin 14 of the eccentric disk 13 so that as the handle 10 is turned and movement is transmitted through 5 the gear 6 to the pinion 8 to cause turning of the eccentric wheel 13, the piston 24 will be reciprocated in the chamber of the cylinder 2 provided about the mounting of the hammer block 17.

10 The piston 24 is notched and cut away at its lower end to form the recess 27 between the body of the piston and the dentil 28, and a hammer 29 has the upper end thereof cut away and notched to provide the recess 30 15 and a dentil 31 similar to the formation on the lower end of the piston 24. This hammer 29 is made of a diameter to fit the cylinder 2 and by fitting the dentil 31 of the hammer into the recess 27 of the piston 24 20 and consequently bringing the dentil 28 of the piston within the recess 30 of the hammer, before these parts are placed within the cylinder 2, a connection is formed which holds the hammer to have movement with 25 the piston, but which at the same time permits a limited degree of flexibility of movement of the one member with respect to the other. The hammer 29 is made of sufficient longitudinal extent that when reciprocated 30 in the cylinder 2 through the movement of the piston 24, movement is exerted by the handle 10, the hammer will strike a blow against the hammer block 17 with each complete revolution of the wheel 13.

35 A handle 32 is provided on the casing 1 to permit the operator to hold the tool properly positioned with one hand while operating the crank handle 10, and as the gear wheel 6 is of a greater dimension than the 40 pinion 8, it will be seen that several blows are struck by the hammer to cause cutting impact of the tool with each turn of the crank handle.

The piston 24 preferably has a more or 45 less fluid tight fit in the cylinder 2 and thus as the piston is moved toward the hammer block 17, air will be compressed within the chamber of the cylinder above the hammer block and in the use of the machine as a 50 driving force for a rock drill, this air compressed in the cylinder can be used to very good advantage to blow the dust and cuttings from beneath the cutting edge 23 of the tool. The drill 19 has a longitudinally 55 formed passage 33 extending through the length thereof and opening at the upper end of the shank 20, and the hammer block 17 has a passage 34 formed centrally thereof in alinement with the passage 33 so that as 60 the piston 24 is moved on the down stroke and air is compressed in the cylinder, this air is forced through the passages 34 and 33 to be discharged in a cleaning blast at the cutting edge or point of the tool. An opening 65 35 is provided through the cylinder 2 to

communicate with the piston chamber thereof and a check valve 36 is located in this opening to permit the supply of air to the piston chamber upon the up stroke of the piston.

With the use of the machine in setting rivets, it will be understood that the drill or tool 19 will be displaced by a tool having a recess or cupped end to give form to the rivet head as the blows are struck, and in 70 this use it will not only not be necessary to use the air blast, but where the machine is used in hot riveting, the air blast would be detrimental, and in this adaptation of the machine, the check valve 36 may be removed 80 from the opening 35 and thus there will be no compression of air to be forced through the passage 34 of the hammer block 17.

While I have shown and described only one specific form of the invention, it will be 85 understood that the socket of the bushing might be made circular in cross section or of any polygonal form to receive the shank of the tool to be used, that bushings having various forms of tool shank receiving openings might be provided, that a connection between the piston and the hammer might be accomplished in a varied manner, and that other changes might be resorted to without departing from the spirit and scope 90 of my invention and hence I do not wish to be limited except to such points as the claims may set forth.

I claim:

1. A drilling machine comprising a cylinder, a bushing mounted in said cylinder at one end thereof and provided with an opening to receive and hold a cutting tool to permit endwise movement thereof, a hammer mounted in said cylinder to be capable of reciprocatory movement to thus direct driving blows against the tool and said hammer recessed at the end away from the head thereof and provided with a dentil disposed to extend transversely, a piston mounted in the cylinder recessed at the end adjacent to the hammer to receive the dentil thereof in a loose fit and provided with a dentil to be received in the recess of the hammer, and means to actuate said piston to have reciprocatory movement in the cylinder and to thus impart this movement to the hammer.

2. A drilling machine comprising a cylinder, a bushing mounted in one end of said cylinder and provided with an opening to receive and hold a cutting tool to permit endwise sliding movement thereof, a hammer block mounted in the cylinder in bearing engagement with the inner end of the tool and arranged to be capable of limited reciprocatory movement, a hammer mounted in the cylinder to be capable of reciprocatory movement into and out of engagement with the hammer block to thus direct driving blows against the tool and recessed 125 130

- at its end to provide a laterally extending dentil, a piston mounted in the cylinder recessed at that end adjacent to the hammer and provided with a laterally disposed dentil, said piston and hammer so formed that the dentil of the one may be fitted in the recess of the other and the hammer will thus be mounted in conjunction with the piston to be positively carried therewith but to have a certain degree of lost movement, and means by which the piston is moved to impart reciprocatory movement to the hammer.
3. A drilling machine comprising a cylinder, a bushing mounted in one end of said cylinder and provided with an opening to receive and hold a cutting tool to permit endwise sliding movement thereof, a hammer block mounted in the cylinder in bearing engagement with the inner end of the tool and arranged to be capable of limited reciprocatory movement, a hammer mounted in the cylinder to be capable of reciprocatory movement into and out of engagement with the hammer block to thus direct driving blows against the tool and recessed at its end to provide a laterally extending dentil, a piston mounted in the cylinder recessed at that end adjacent to the hammer and provided with a laterally disposed dentil, said piston and hammer so formed that the dentil of the one may be fitted in the recess of the other and the hammer will thus be mounted in conjunction with the piston to be positively carried therewith but to have a certain degree of lost movement, said tool and hammer block provided with registering passages extending into the cylinder, the piston being arranged in a manner that on its down stroke to bring the hammer against the hammer block it will compress air within the cylinder to be forced through the registering and aligned passages to blow the cuttings from the working end of the tool, and a valved inlet passage to supply air to the cylinder.
4. A drilling machine comprising a cylinder, a bushing mounted in one end of said cylinder and provided with an opening to receive and hold a cutting tool to permit endwise sliding movement thereof, a hammer block mounted in the cylinder in bearing engagement with the inner end of the tool and arranged to be capable of limited reciprocatory movement, a hammer mounted in the cylinder to be capable of reciprocatory movement into and out of engagement with the hammer block to thus direct driving blows against the tool and recessed at its end to provide a laterally extending dentil, a piston mounted in the cylinder recessed at that end adjacent to the hammer and provided with a laterally disposed dentil, said piston and hammer so formed that the dentil of the one may be fitted in the recess of the other and the hammer will thus be mounted in conjunction with the piston to be positively carried therewith but to have a certain degree of lost movement, a casing connected with that end of the cylinder within which the piston works, an eccentric mounted in said casing, a connecting rod extending from the eccentric to the piston, and manually actuatable means to turn said eccentric to cause reciprocatory movement of the piston and to thus accomplish the driving blows against the tool.
- In testimony whereof I affix my signature in presence of two witnesses.

FRANK MAROVITCH.
